UNITED STATES PATENT OFFICE

170,494

TOY FIGURE

Eunice B. Darroch, Livingston, Mont.

Application May 11, 1953, Serial No. 24,952

Term of patent 14 years

(Cl. D34—2)

To all whom it may concern:

Be it known that I, Eunice B. Darroch, have invented a new, original, and ornamental Design for a Toy Figure, of which the following is a specification, reference being had to the accompanying drawing, forming a part hereof.

Fig. 1 is a perspective view of a toy figure, showing my new design; Fig. 2 is a top plan view of the same; and Fig. 3 is a side elevational view of the same.

I claim:

The ornamental design for a toy figure, as shown.

EUNICE B. DARROCH.
